SKILLET OR SIMILAR ARTICLE

John Di Lorenzo, 235 W. 46th St.,
New York, N.Y. 10036

Filed Feb. 7, 1972, Ser. No. 224,414

Term of patent 3½ years

Int. Cl. D7—02

U.S. Cl. D7—85

FIG. 1

FIG. 2

FIG. 3

FIG. 4

FIG. 1 is a top perspective view of a skillet or similar article showing my new design;

FIG. 2 is a bottom plan view thereof;

FIG. 3 is an elevational view of the side opposite that shown in FIG. 1; and

FIG. 4 is an end elevational view thereof as seen from the left of FIG. 3.

I claim:

The ornamental design for a skillet or similar article, substantially as shown.
